DESIGN FOR A CAPE.

Design No. 6,633, dated May 6, 1873

UNITED STATES PATENT OFFICE.

MARTIN LANDENBERGER, JR., OF PHILADELPHIA, PENNSYLVANIA.

DESIGN FOR A CAPE.

Specification forming part of Design No. **6,633**, dated May 6, 1873; application filed April 8, 1873.

To all whom it may concern:

Be it known that I, MARTIN LANDENBERGER, Jr., of Philadelphia, Pennsylvania, have invented a Design for a Garment, of which the following is a specification:

My design for a circular garment is clearly represented by the figure in the accompanying drawing. It is of the usual semicircular or nearly semicircular shape, and has a triangular hood, A, both the latter and the body of the garment being edged with a deep fringe, a, of the character represented, and the hood, which is divided in the center, is ornamented by a row of buttons, b, by a cord, c, and by cords and tassels e, f, and g, all arranged in a manner too clearly shown by the drawing to re-

quire minute description. The garment is split or slashed at the back, as shown at h, but this may be omitted, and forms no part of the design.

Irrespective of the colors employed, I claim—

The design for a circular garment, substantially as described, and as represented in and by the accompanying drawing.

In testimony whereof I have signed my name to this specification in the presence of two subscribing witnesses.

MARTIN LANDENBERGER, JR.

Witnesses:

J. J. BUCHEY,
JNO. JAY WARD.
